(57) **CLAIM**

We claim the ornamental design for an end cap for an LED stick, as shown and described.

DESCRIPTION

FIG. 1 is an isometric view of an embodiment of an end cap for an LED stick, showing our new design;

FIG. 2 is front elevation thereof;

FIG. 3 is rear elevation thereof;

FIG. 4 is a right elevation thereof;

FIG. 5 is a top plan view thereof; and,

FIG. 6 is a cross-sectional view thereof.

The left elevation is a mirror image of the right elevation and the bottom plan view is the same as the top plan view, but rotated 180 degrees.
